CLAIM

The ornamental design for a cartridge for clinical analyzer as shown and described.

DESCRIPTION

FIG. 1 is a front, top and right side perspective view of a cartridge for clinical analyzer according to the design; FIG. 2 is a front, bottom and left side perspective view thereof;

FIG. 3 is a front view thereof;

FIG. 4 is a left side view thereof;

FIG. 5 is a right side view thereof;

FIG. 6 is a top view thereof;

FIG. 7 is a bottom view thereof;

FIG. 8 is a rear view thereof; and,

FIG. 9 is a cross-sectional view taken along line 9-9 of FIG. 3.

The broken lines illustrate portions of the cartridge for clinical analyzer that form no part of the claimed design.

1 Claim, 7 Drawing Sheets
